TOOL FOR APPLYING CLIPS

Ward Joseph Kremkau, Jr., Mechanicsburg, Pa., assignor to AMP Incorporated, Harrisburg, Pa.

Filed May 18, 1965, Ser. No. 85,341

Term of patent 14 years

(Cl. D54—13)

I claim:

The ornamental design for a tool for applying clips, as substantially shown and described.
